UNITED STATES PATENT OFFICE.

HENRY R. GILSON, OF BADEN, PENNSYLVANIA.

DESIGN FOR AN ELECTRICAL FIXTURE.

47,104.

Specification for Design.

Patented Mar. 16, 1915.

Application filed August 7, 1914. Serial No. 855,703. Term of patent 14 years.

To all whom it may concern:

Be it known that I, HENRY R. GILSON, a citizen of the United States, residing at Baden, in the county of Beaver and State of Pennsylvania, have invented a new, original, and ornamental Design for an Electrical Fixture, of which the following is a specification, reference being had to the accompanying drawing, forming part thereof.

The figure is a perspective view of an electrical fixture showing my new design.

I claim:

The ornamental design for an electrical fixture as shown.

HENRY R. GILSON.

Witnesses:

PAUL N. CRITCHLOW,
FRANCIS J. TOMASSON.
